(57) **CLAIM**

The ornamental design for a car sunshade, as shown and described.

DESCRIPTION

FIG. 1 is a rear perspective view of a car sunshade, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged detail view of area **8** in FIG. 1; and,

FIG. 9 is an enlarged detail view of area **9** in FIG. 2.

The dash-dot-dash broken lines encircling the enlarged views are for annotative purposes only and form no part of the claim thereof.

1 Claim, 9 Drawing Sheets
